(57) **CLAIM**

The ornamental design for a heavy duty, full energy, encoder driven non-handed electric door operator, as shown and described.

DESCRIPTION

FIG. 1 is a front view of the heavy duty full energy, encoder driven non-handed electric door operator showing my new design.

FIG. 2 is a back view of FIG. 1.

FIG. 3 is a left side elevation view of FIG. 1.

FIG. 4 is a right side elevation of FIG. 1.

FIG. 5 is a top view of FIG. 1.

FIG. 6 is a bottom view of FIG. 1.

FIG. 7 is a front left perspective view of FIG. 1; and,

FIG. 8 is a back right perspective view of FIG. 1.
